UNITED STATES PATENT OFFICE.

LORING D. BURWELL, OF MINNETONKA MILLS, MINNESOTA, ASSIGNOR TO WESTINGHOUSE ELECTRIC & MANUFACTURING COMPANY, A CORPORATION OF PENNSYLVANIA.

UNDERFEED STOKER.

Application filed February 20, 1924. Serial No. 694,004.

My invention relates to underfeed stoker furnaces, particularly to multiple retort stokers having a fuel supporting grate inclined from the front to the rear of the furnace and along which fuel is caused to travel with the aid of gravity, and it has for an object to provide means in a stoker of the character designated which shall assist in the maintenance of a uniformly rearwardly moving fuel bed of substantially uniform permeability to air, to the end that a more even distribution of the fuel and air throughout the fuel bed, and hence a more complete and efficient combustion of the fuel, may be attained.

The objects of my invention may be secured by the employment of the apparatus illustrated in the accompanying drawing in which Fig. 1 is a fragmentary view in longitudinal section through the center of a retort of an underfeed furnace illustrating an embodiment of my invention; Fig. 2 is a fragmentary plan view of the lower portion of the stoker illustrated in Fig. 1; Fig. 3 is a plan view on an enlarged scale of a tuyère construction shown in Fig. 1; Fig. 4 is a view in section taken on line IV—IV of Fig. 3; Fig. 5 is a view in vertical section of one of the water supply reservoirs illustrated in Fig. 2; Fig. 6 is a fragmentary view in longitudinal section through the center of a retort showing a modified form of my invention applied to a different type of stoker from that illustrated in Figs. 1 and 2; and Fig. 7 is a plan view of the retort bottom plate shown in Fig. 6.

It has been heretofore difficult in the operation of multiple retort stokers to maintain a uniformly moving fuel bed due to the formation of clinkers adjacent the rear of the stoker which offer material resistance to the rearward movement of the fuel bed. These clinker formations, further, give to the fuel bed characteristics which inhibit the even distribution of air through the fuel bed with a consequent lack of uniformity in the rates of combustion at different portions of the fuel bed.

The underlying idea of the present application is based upon the fact that a more uniform rate of combustion throughout the fuel bed and a more complete and efficient combustion of the fuel can be secured, and, indeed, more fuel per unit of grate surface can be effectively burned in an underfeed

furnace, if a fuel bed of substantially uniform thickness and uniform air distributing capacity can be made to traverse the grate with equal rates of advancement from the entrance throat to the dump mechanism. 60 Applicant perceived that this method of combustion had not heretofore been possible of attainment because the almost completely burned fuel and clinker at the lower end of the furnace travels toward the discharge 65 with a greater resistance to movement, due to the semi-plastic condition of the refuse and of the nearly burned fuel, than does the fuel at the upper portions of the grate. Consequently the oncoming fuel backs up 70

behind the retarded fuel at the rear of the furnace to form a heap large enough to exert sufficient pressure on the lower parts of the fuel bed to overcome the added resistance to its rearward movement and to force it on 75 to the discharge mechanism. Such heaps were heretofore considered to constitute the natural fuel bed contour.

Applicant conceived the idea of minimizing this heaped fuel bed contour by lessening the resistance to the movement of the fuel at the rear of the underfeed grate, thus securing the advantages of a fuel bed of uniform thickness through which air for supporting combustion could be more uniformly distributed. In other words, by making the resistance to movement of the fuel bed over the supporting metal of the grate substantially the same throughout the length of the fuel movements, the tendency 80 to heaping of the fuel would be eliminated and it would be possible to maintain a fuel bed of substantially uniform thickness throughout the combustion area of the grate. 85

This result is accomplished in the present 90 invention by adding to the air supply at the lower portion of the grate sufficient quantities of water to harden the surface of the semi-plastic refuse of the nearly consumed fuel so that it slides over the lower grate 100 portions with the same facility that the fuel slides along the upper portions of the grate surface, at the same time transforming the refuse so treated into a porous condition which permits free passage of air there-through.

A fuller understanding of my invention may be had by reference to the drawings in which I show at 10 an underfeed stoker of the multiple-retort type having inclined 110

tuyère banks 11, retorts 12, discharge mechanism 13, hopper 14 and plunger 15, all of a conventional construction. The lower end of each of the retorts 12 is provided with 15 tuyère plates 16, which plates cooperate with the lower ends of the tuyère banks 11 to support the rear portion of the fuel bed, that is, the ash and the nearly consumed fuel, prior to its delivery to the dump mechanism 13.

In carrying out my invention in connection with the stoker of the above described character, water is introduced with the air to the fuel bed at one or more zones in the 15 rearward travel of the fuel. The number and disposition of these water supply devices may be varied somewhat to meet different operating conditions arising by reason of the character of the ash content of 20 the fuel. Where the fuel contains a large percentage of ash which is of low fusibility, the water-introducing devices should be increased in number and placed in higher positions. By way of illustration of an embodiment of my invention which has proven satisfactory in operation for the usual low grade fuels, I show two water distributing systems, one for supplying water to tuyères of the tuyère banks 11 and the other for supplying water to the retort tuyères 16.

The water distributing system associated with the tuyère banks 11 comprises a manifold 20 extending transversely beneath the tuyère and retort supports of the stoker and 35 provided with risers or branch pipes 21 having their upper ends 22 laterally formed to discharge in a horizontal direction. As is more clearly shown in Figs. 1, 2 and 6, each of the horizontally extending nipples 22 is 40 disposed within one of the air ports 25 of the tuyère 11 and is preferably so located that the air being discharged through the port 25 surrounds the nipple 22. The nipple 22 should preferably terminate within 45 the port 25 so that it will not be subjected to the heat of the burning fuel.

The manifold 20 extends outwardly through the side wall 27 of the furnace where it is provided with a branch 28 having a valve 29 and leading into an elevated reservoir 30. The reservoir 30 should be located at such a level as to discharge water through the nipples 22 with a pressure head. Suitable means are provided for maintaining 55 a uniform pressure head at the nipples 22 and also for varying the extent of this pressure head as changed combustion conditions may require. As shown in Fig. 5, an inlet pipe 31, provided with a valve 32, supplies water to the reservoir 30. A float 33 within the reservoir 30 has a depending guide stem 34 engaging a guide 35 and also a stem 36 extending upwardly through the top or cover 37 of the reservoir 30. A suitable link and lever system 38 fulcrumed at

39 upon a post 40 carried by the cover 37, connects the float 33 and the valve 32 in such a manner that the water admitted to the reservoir 30 is at all times sufficient to maintain a predetermined level therein. The 70 stem 36 is connected to the lever mechanism 38 by means of an adjustable connection 41, which may be of any well-known form.

The water distributing system for the retort tuyères comprises a manifold 50 extending transversely beneath the tuyère supporting structure and provided with risers 51 which supply water to specially constructed tuyères 52. Each tuyère 52 is provided with a shallow basin 53 into which a 80 riser 51 discharges water through an adjustable cap or nipple 54, hereinafter more fully described. An opening 56 for interlocking the tuyère 16 disposed above the special tuyère 52 is preferably formed with an upwardly extending boss 57, to prevent the leakage of water from the basin 53. Fluted channels or corrugations 58 lead from the basin 53 to the rear edge of the tuyère 52 and serve to direct both the air, which 90 passes over the water in the basin 53 on its way from the air chamber beneath the stoker, and water from basin 53 to the fuel bed in the zone of the exposed surface 59 of the tuyère 52.

As is shown in the drawing, any header 50 is capable of supplying water only to the tuyères 52 which are disposed in substantially the same horizontal plane, and since the water overflows from the basin 53 through the channels 58 it is essential that some means for accurately proportioning the water to the several tuyères 52 be provided. This is accomplished in the construction illustrated in Fig. 4 by providing an externally and interiorly threaded cap 54 for the upper end of the pipe 51. The tuyère 52 is provided with a threaded opening 60 into which the threaded cap 54 is turned. A hole 61 near the upper end of the cap 54 provides an outlet for the water rising within the header 51. To regulate the relative amounts of water delivered through each of the several caps 54, it is only necessary to raise or lower the opening 61 by screwing the cap up or down in the opening 60 of the tuyère 52. The header 50 is supplied with water from a reservoir 62, provided with means for controlling the pressure head in the header 50 in all respects similar to that described in connection with the reservoir 30.

Having described an embodiment of my invention, the operation thereof is herein briefly set forth. Assuming that combustion has been initiated and that fuel is being supplied to the underfeed grate and is moving rearwardly toward the discharge mechanism in the conventional manner, the valves in the manifolds 20 and 50, respective-

- ly, are opened and water is permitted to flow from the reservoirs 30 and 62 through the manifolds 20 and 50, respectively, to the air discharging tuyères associated therewith.
- 5 The float 33 is set by means of the adjusting member 41 to maintain a predetermined level of water in the reservoir 30 above that of the discharge ends of the nipples 22. A small full stream of water is thus caused to
- 10 be discharged from the nipples 22 which being centrally disposed in an air discharging tuyère 25 permits the air blast to carry the water mixed more or less therewith to the fuel bed. If the nipples 22 have been dis-
- 15 posed in a zone of travel of the fuel at which the partially burned fuel begins to assume a plastic condition, the action of the water upon the fuel is to make the clinker porous, thereby permitting free passage of air there-
- 20 through, and to harden or form a glass-like crust upon the surfaces of the fuel which come in contact with the water. The partially burned fuel is then in a condition to facilitate complete combustion of unburned
- 25 portions and to slide easily over the metal surfaces of the fuel supporting elements. The nipples 22 should be at the same level, since a full stream of water under a low head is distributed to each nipple and con-
- 30 sequently any substantially irregularity in the level of the several nipples materially affects the amount of water discharged therefrom. It is also preferable to place the nipples 22 at such an angle that the water dis-
- 35 charged therefrom not only affects the burning fuel immediately over the tuyère banks, but also the character of the fuel within the retorts.
- Where a number of tuyère plates form the
- 40 bottom of the rear end of the retort, it is also desirable to introduce water into the air discharged through one or more of these retort tuyères into the fuel bed. The tuyères selected for accomplishing this result are
- 45 preferably nearer the rear end of the stoker than those of the tuyère banks selected for the introduction of water with the air. In the retort tuyère disclosed in Figs. 1 to 4, water is admitted with the air through the
- 50 entire width of the tuyère and serves to af-
- 55 fect not only the fuel passing over the retort tuyère, but also the fuel which is contiguous to the sides of the tuyères of the tuyère bank. This arrangement prevents adhesions of the hot fuel refuse not only upon the retort bottom but at the angles between the retort tuyères and the side walls where adhesion of clinker masses readily takes place in the ordinary underfeed stoker. By a suitable
- 60 disposition of the water distributing devices above described, it is possible to maintain the fuel passing over the lower portions of the stoker grate in such condition that air for supporting combustion readily passes there-
- 65 through and no greater resistance is offered to its passage over the supporting surfaces of the grate than takes place in the upper portion of the grate. It consequently follows that the fuel moves rearwardly along the grate at a substantially uniform speed
- 70 and hence permits the fuel bed over the tuyère banks to maintain a substantially uniform thickness throughout the entire course of the fuel travel through the furnace.
- In Figs. 6 and 7, I show a modified form
- 75 of my apparatus, applicable to an underfeed stoker having dead plates at the rear of the bottom of the retorts instead of the tuyère plates of Figs. 1 to 4, the members 11', 20'
- 80 21', 22', 25', and 50' corresponding to the members 11, 20, 21, 22, 25 and 50 respectively of Figs. 1 to 4 inclusive. In stokers of this type I employ specially constructed dead plates, preferably a rear dead plate 70,
- 85 and a second dead plate 71. Each of the dead plates 70 and 71 is provided at its forward end with a depression or basins 73 from which extends rearwardly corrugations or channels 74. Water is supplied to the basins 73 from the manifold 50 by means of
- 90 risers 75. Means for regulating the relative flow of water to the basins 73, similar to that employed in connection with the retort tuyère 52, is employed. As shown in Fig.
- 95 6, the dead plates 70 and 71 are each provided with a depending tapped boss 76 beneath the basins 73. The risers 75 are threaded into the lower portions of the bosses 76 and nozzles 78 are threaded into the bottom of the basins, to communicate with
- 100 the risers 75. The nozzles 78 have side outlet openings 79 to direct the water into the basins 73, which outlets may be raised or lowered to regulate the flow of water therethrough by simply screwing the nozzles 78
- 105 out of or into the bottoms of the basins.
- The forward dead plates 71, as shown,
- 110 have uprising flanges 80 in which are air emitting openings 81, located to direct a blast of air into the fuel bed over dead plates. The air issuing from the openings 81 entrains some of the water from the basins 73 and in this way assists in distributing the moisture to the fuel.
- The water discharged from the nozzles 22
- 115 and 78 and the caps 54 is under a relatively low pressure head and consequently, where the water employed is not free from solid impurities, the water distributing members may become clogged and prevent a proper
- 120 functioning of the stoker. It is, therefore, desirable to provide in connection with the manifolds 20 and 50 some means for flushing the small distributing connections. In
- 125 Fig. 5, mechanism for accomplishing this end is illustrated. As there shown, a branch 90, provided with a valve 91, leads from the pipe 31 at the inlet side of valve 32 and connects with the manifold 20 through a T-fitting 92. An air pipe 94, in alignment with
- 130

and of lesser diameter than the manifold 20, projects within the T-fitting 92 in such manner as to form an ejector nozzle 93. A valve 95 in the pipe 94 controls the flow of air therethrough.

Where flushing of the water distributing pipes is required, it should be done at regular intervals, preferably once a day, or in some cases oftener. In flushing, the header 10 20 and its distributing connections, for example, the valve 29 is closed and the valves 91 and 95 are opened. The air needed for this purpose is preferably taken from the shop air line, in which a pressure in the 15 neighborhood of 100 to 150 pounds is commonly maintained. The high pressure air discharged from the nozzle 93 entrains water from the pipe 90 and thus forces through the manifold 20, risers 21 and nozzles 22 an intimate mixture of air and water under high pressure. A short period of 20 operation is sufficient to remove all impurities from the water distributing system being cleaned.

25 It has been found that a high pressure mixture of air and water has greater cleansing capabilities than either air or water used alone. Satisfactory results have been obtained, however, where water alone has 30 been used as a flushing agent, particularly where high pressure water is available for the flushing action, and, consequently, I do not desire to limit the present invention to the use of an air-water mixture as flushing 35 agent.

While I have shown my invention in but two forms, it will be obvious to those skilled in the art that it is not so limited, but is susceptible of various other changes and 40 modifications, without departing from the spirit thereof, and I desire, therefore, that only such limitations shall be placed thereupon as are imposed by the prior art or as are specifically set forth in the appended 45 claims.

What I claim is:—

1. In an underfeed stoker having series of alternating retorts and tuyère banks, means for introducing water into a lower portion 50 of each of the retorts for minimizing adhesions of the refuse thereto.

2. In an underfeed stoker having series of alternating retorts and tuyère banks, means for introducing water through the tuyère banks into the lower portion of each 55 of the retorts for minimizing adhesions of the refuse thereto.

3. In an underfeed stoker having series of alternating retorts and tuyère banks, means for delivering water to a lower portion 60 of a tuyère bank for minimizing adhesions of the refuse thereto.

4. In an underfeed stoker, the combination 65 of a plurality of retorts, tuyère banks forming fuel supporting and air supplying

means between the retorts, said tuyère banks being provided with channels for discharging air into said retorts, and means for introducing water in a lower portion of each of said retorts through one or more of said 70 channels.

5. In an underfeed stoker, the combination of a plurality of retorts, tuyère banks forming fuel supporting and air supplying means between the retorts, said tuyère banks 75 being provided with channels for discharging air into said retorts, and means for introducing water in a lower portion of each of the retorts concomitantly with the air through one or more of said channels. 80

6. In an underfeed stoker, the combination of a plurality of retorts, tuyère banks forming fuel supporting and air supplying means between the retorts, said tuyère banks being provided with channels so disposed 85 as to discharge air both rearwardly and laterally, and means for introducing water with the air discharged from one or more of said channels.

7. In an underfeed stoker, the combination of a plurality of retorts, tuyère banks forming fuel supporting and air supplying means between the retorts, said tuyère banks being provided with channels so disposed 95 as to discharge air both rearwardly and laterally, a header disposed transversely to the retorts and extending therebeneath, and branch pipes leading from said header into some of said channels for the introduction of water into the air discharged therefrom. 100

8. In an underfeed stoker, the combination of a plurality of retorts, tuyère banks forming fuel supporting and air supplying means between the retorts, said tuyère banks being provided with channels so disposed as 105 to discharge air both rearwardly and laterally, pipes leading into some of said channels for the introduction of water into the air discharged therefrom, and means for supplying water to said pipes. 110

9. In an underfeed stoker, the combination of a plurality of retorts, tuyère banks forming fuel supporting and air supplying means between the retorts, said tuyère banks being provided with channels so disposed as 115 to discharge air both rearwardly and laterally, pipes leading into some of said channels for the introduction of water into the air discharged therefrom, and automatic means for maintaining a uniform head of 120 water in said pipes.

10. In an underfeed stoker, the combination of a plurality of retorts, tuyère banks forming fuel supporting and air supplying means between the retorts, said tuyère banks 125 being provided with channels so disposed as to discharge air both rearwardly and laterally, pipes leading into some of said channels for the introduction of water into the air discharged therefrom, means for sup- 130

- plying water to said pipes, automatic means for maintaining a uniform head of water in said pipes, and means for adjusting the automatic means to vary the head of water with in predetermined operative limits.
- 5 11. In an underfeed stoker having series of alternating retorts and tuyères, means for introducing water into a lower portion of the fuel bed supported by said retorts and 10 tuyères.
12. In an underfeed stoker having series of alternating retorts and tuyères, means for introducing in limited quantities of water under a relatively low pressure head into 15 a lower portion of the fuel bed supported by said retorts and tuyères.
13. In an underfeed stoker having series of alternating retorts and tuyères, means for introducing a plurality of streams of water 20 under relatively low pressure into a lower zone of the fuel bed supported by said retorts and tuyères, said zone extending substantially the width of the stoker.
14. In a furnace grate, tuyère blocks for discharging air into the fuel bed including a 25 plurality of tuyère blocks disposed in the same general horizontal plane, conduit means for supplying water under a low pressure head to the tuyères in said plane for facilitating the combustive action of the 30 fuel, and means for forcing high pressure water through said conduit means for clearing foreign matter therefrom.
15. In a furnace grate, tuyère blocks for discharging air into the fuel bed including a 35 plurality of tuyère blocks disposed in the same general horizontal plane, conduit means for supplying water under a low pressure head to the tuyères in said plane for facilitating the combustive action of the 40 fuel, and means for passing mixed air and water under a high pressure head through said conduit means for clearing foreign matter therefrom.

In testimony whereof, I have hereunto 45 subscribed my name this 14th day of January, 1924.

LORING D. BURWELL.
